UNITED STATES PATENT OFFICE.

GUY E. BARDSHAR, OF SANDUSKY, OHIO.

ROLLER-BLOTTER.

SPECIFICATION forming part of Letters Patent No. 669,040, dated February 26, 1901.

Application filed June 19, 1900. Serial No. 20,868. (No model.)

To all whom it may concern:

Be it known that I, GUY E. BARDSHAR, a citizen of the United States, residing at Sandusky, in the county of Erie and State of Ohio, 5 have invented new and useful Improvements in Roller-Blotters, of which the following is a specification.

My invention relates to blotters, and more particularly to roller-blotters. The advantages obtained by the same are an improved article of this description, which combines the several qualities of artistic design, usefulness, and durability.

I am aware that roller-blotters have been 15 constructed by winding a strip of blotting-paper on a spool or bobbin and then securing the ends of the same. In this class of devices, as in all other blotting contrivances with which I am acquainted which use paper 20 as the absorbent, the flat or finished surface of the paper is employed. This surface because of its finish is, as is well known, not a perfect absorbent. It is liable to smear heavy writing, such as signatures.

25 My invention has for its object to obviate this difficulty, and with that end in view I construct a blotter the blotting-surface of which is formed of the cut edges of the paper. This construction makes an almost perfect 30 blotting-surface, or at least the best which can be obtained by using paper. Such a blotter is particularly adapted for use in blotting signatures. This method of construction enables me to make at no additional expense a 35 blotter which presents an artistic appearance to the eye, as I can use disks of different colors and by alternating them make many different designs. This will be recognized as being a very important feature in this class 40 of novelties.

The mechanical parts of my device are so designed that a new roller can be readily substituted for the old one or new paper put on the old roller if it is desired to retain the same. 45 I do not wish to be restricted as to mechanical details, as these may be varied in many particulars without departing from the spirit of my invention.

In the drawings which accompany this 50 specification and of which they form a part,

Figure 1 is a perspective of my improved blotter. Fig. 2 is a longitudinal section through the axle of the same with parts broken away. Fig. 3 is a longitudinal section of a modified form of my device. Fig. 4 is a longitudinal 55 section of a second modified form.

In the drawings like numerals of reference denote like parts wherever they occur.

The numeral 1 designates the axle of my device, which has a longitudinal aperture 2. 60 This aperture is enlarged at each end to form portions 3, which form bearings for the handle. Secured on the axle 1 near its ends are collars 4, which are kept from slipping off by rims 5, formed integral with axle 1. Threaded on 65 the axle 1 are a large number of blotting-paper disks 6. These disks are circular and are threaded on the axle before the collars are placed thereon, or I may vary the construction, so as to make the disks removable at 70 pleasure. Disks 6 are held or clamped firmly in place by the collars 4 and form a compact whole. They may be of different colors. For example, I may first put on a number of yellow ones, then a number of white ones, then 75 a number of blue ones, then the same number of white ones as before, and then finally the same number of yellow ones as before, thus forming a beautiful symmetrical design. The handle 7 is formed of a single piece of resilient 80 wire, appropriately curved to intensify the spring action and provided with portions 8 to serve as pintles. The portions 8 fit the enlarged portions 3 and may be easily inserted 85 therein by springing the members of said handle apart. The parts 8 will be held in this position, after being inserted, by the clamping action of the handle. If it is found desirable to modify this clamping action, I may insert a cylindrical core 9 into the aperture 2, thus 90 keeping the members of the handle apart, and thereby dispense with the enlarged portions 3, as is illustrated in Fig. 3. I may also make my axle 1 in two sections 1^a and 1^b, the section 1^a fitting over 1^b, as shown in Fig. 4. 95 The clamping action of the handles will hold the two portions together, and new paper may be placed on the axle by simply detaching the handle 7 and separating the two sections 1^a and 1^b.

Having thus described my invention, what I claim, and wish to secure by Letters Patent, is—

In a roller-blotted, the combination, substantially as described, of circular disks of blotting-paper, a tubular axle comprising two parts one fitting within the other and disks mounted on the outer ends of said axle to secure said disks of blotting-paper, and a handle formed of a single piece of resilient wire

and adapted to fit said axle and by its spring action to clamp and hold the two parts of the said tubular axle together.

In testimony whereof I have hereunto set my hand in presence of two subscribing witnesses.

GUY E. BARDSHAR.
